UNITED STATES PATENT OFFICE.

RICHARD SNOECK, OF NEW YORK, N. Y.

CURTAIN.

1,420,455.

Specification of Letters Patent. Patented June 20, 1922.

Application filed September 2, 1921. Serial No. 497,815.

To all whom it may concern:

Be it known that I, RICHARD SNOECK, a citizen of the United States, and resident of the city of New York, borough of Manhattan, county of New York, and State of New York, have invented a new and Improved Curtain, of which the following is a full, clear, and exact description.

In connection with automotive vehicles of the non-enclosed type, such as touring cars and roadsters, it is a well appreciated fact that it has been customary for the manufacturer to provide what are known as side curtains to prevent the entrance of rain into the tonneau of the vehicle.

These curtains to say the least have presented extremely unsightly appearances, and aside from this objection difficulty has been experienced in that when they were in applied position an operator was incapable of extending his hand beyond the body of the vehicle to indicate turning, stopping, etc., as is required by law.

Also numerous accidents have occurred incident to the use of these curtains in that the visibility is extremely bad through the transparent elements provided and thus it has been not unusual for any number of unavoidable collisions to occur, incident to the use of the same.

Thus it is an object of my invention to provide a curtain adapted to be arranged between the top and body of a motor vehicle, and which shall primarily present a neatness of appearance, corresponding to that of a sedan or coupe type of motor vehicle, although the said curtain is instantly detachable when this is desired.

A further object of my invention is the construction of a device of the nature specified, by means of which an operator, although protected from the action of the elements, will be capable of extending his arm beyond the body of the vehicle for signalling purposes, or to readily observe through the body of the curtain objects beyond the vehicle.

Another object of this invention is the construction of a side curtain by means of which an occupant of a vehicle may be enabled to extend his head beyond the body of the vehicle for the purpose of observation, if this should become necessary.

Still another object of my invention is the construction of a curtain by means of which portions of curtains now forming a stand-

ard part of the equipment of a motor vehicle may be utilized, although the entire device may be constructed of new material if this is desired.

Still a further object of my invention is the provision of a side curtain which in addition to embodying the features set forth in the preceding paragraphs will also be extremely simple in construction and economical in manufacture.

Further objects of this invention will appear in the annexed specification taken in connection with the drawings, which latter illustrate one practical embodiment of the same, and in which;

Figure 1 is a fragmentary front view of the forward portion of a motor vehicle, and showing a curtain of my improved type interposed between the top and body thereof.

Figure 2 is a sectional view taken along the line 2—2 of Figure 1.

Figure 3 is a transverse sectional view taken along the line 3—3 and in the direction of the arrows also indicated in Figure 1.

Figure 4 is a perspective view of my improved attachment.

Figure 5 is a fragmentary perspective view showing in detail certain of the construction thereof, and

Figure 6 is an enlarged view of a certain part of the device as illustrated in Figure 4.

Referring now more particularly to Figure 1 it will be seen that the reference numeral 10 indicates the body of the vehicle presenting the conventional wind shield 11, and also being provided with a top 12 between which the side curtains 13 are disposed, these latter members being retained in applied position by suitable panels 14.

According to conventional construction, it has been customary to provide panels of isinglass in the curtains 13, but it will be noted reference being had to Figures 1, 2 and 3 that I substitute in lieu thereof transparent panels 15, preferably of glass, these latter being mounted and slidably retained by means of a construction hereinafter more clearly specified. However it will be appreciated that although in the embodiment illustrated my invention is shown as applied to the curtains adjacent the driver's seat, for which application it is primarily intended, that the same is equally adaptable to the curtain in any position.

With a view of providing a mounting for

the panel 15, it will be noted primarily that an opening is formed in the curtain 13, which opening is preferably of a size slightly less than the aggregate size of these 5 panels. As in Figures 2, 3 and 5, the edge of the curtain adjacent its opening is formed into a bead by preferably coiling its edge around a wire 16. A channel frame 17 including a plurality of side members has its 10 outer edge bent as at 18 to provide a trough, and thus it will be understood that the frame may be applied to the curtain by simply holding these elements in their proper position, and in pinching the bent portion 18 15 so as to close the trough around the bead of the curtain 13. Mounted within the frame 17 is a strip 19 formed with grooves 20 within which the panels 15 slidably rest, and it is to be noted that the strip 19, although 20 capable of being constructed of any desirable material is preferably of rubber.

Now with a view of permitting of the association of the panels 15 with the frame, it will be noted, as in Figures 4 and 6, that one 25 of the side members 21 of the frame is rockingly secured, as at 22, to the body of this member. Thus it is capable of being swung to one side so as to give access to the grooved strip 19, obviously allowing the panels 15 to 30 be inserted into or completely withdrawn from the frame when this becomes necessary.

Thus it will be appreciated that an extremely neat curtain is provided, which may 35 be constructed at a minimum figure, and by means of which an operator will be protected from the elements, it being noted that the objection incident to the cracking of the isinglass as has been customary in usual curtains is avoided.

Further an operator is enabled to slide one of the panels 15 so as to be capable of

extending his head or hand beyond the curtain for the purpose of observation or signalling.

45

Thus all of the objects set forth in the preamble of this specification are accomplished, and it will be understood that numerous modifications of structure might readily be resorted to without in the least departing from the spirit of my invention, which I claim is:

1. A curtain including a body of flexible material, a channel frame secured to said body, a grooved strip carried by said frame, 55 panels mounted within said strip, one of the portions of said frame being capable of being swung to one side of the body thereof, for permitting of the complete withdrawal from or the insertion of said panels into 60 said grooved strip.

2. A curtain including a bead of flexible material formed with a cutout portion, a rigid channel frame having one of its side walls bent to provide a trough shaped portion, a bead forming a part of said flexible body, and disposed adjacent the cutout portion thereof, said bead being adapted to lie within said trough shaped portion, a strip of grooved material disposed within the 70 channel of said frame, a plurality of panels mounted within said grooves, and means forming a part of said frame for permitting of the removal or insertion of panels from said frame.

75

3. A curtain including a body of flexible material formed with an opening, a rigid frame adapted to be connected to said body and adapted to lie within said opening, a side member forming a part of said frame 80 and swingingly connected thereto, and panels carried by said frame.

RICHARD SNOECK.
